CLAIM

The ornamental design for a greeting card and sign, as
shown and described.

DESCRIPTION

A portion of the disclosure of this patent document contains
material which is subject to copyright protection. The copy-
right owner has no objection to the facsimile reproduction
by anyone of the patent document or the patent disclosure,
as it appears in the Patent and Trademark Office patent file
or records, but otherwise reserves all copyright rights what-
soever.

FIG. 1 is a perspective view of the greeting card and sign,
illustrating my new design;

FIG. 2 is a front elevational view of the greeting card and
sign;

FIG. 3 is a rear elevational view of the greeting card and
sign;

FIG. 4 is an elevational view of one side of the greeting card
and sign;

FIG. 5 is an elevational view of the other side of the greeting
card and sign;

FIG. 6 is a top plan view of the greeting card and sign; and,
FIG. 7 is a bottom plan view of the greeting card and sign.
The broken line showing of texts is included for the purpose
of illustrating environmental structure and forms no part of
the claimed design.
